UNITED STATES PATENT OFFICE.

LOUIS V. ARONSON, OF NEWARK, NEW JERSEY.

DESIGN FOR A CASING FOR A CIGARETTE DISPENSER.

Application filed April 20, 1926. Serial No. 17,356. Term of patent 7 years.

To all whom it may concern:

Be it known that I, LOUIS V. ARONSON, residing at Newark, in the county of Essex and State of New Jersey, have invented a new, original, and ornamental Design for a Casing for a Cigarette Dispenser, of which the following is a specification, reference being had to the accompanying drawing, forming part thereof, in which is shown a perspective view of the article showing my new design.

I claim:

The ornamental design for a casing for a cigarette dispenser, as shown.

LOUIS V. ARONSON.
